United States Patent Office.

WILLIAM H. ROBERTS, OF MAUCH CHUNK, PENNSYLVANIA.

Letters Patent No. 100,449, dated March 1, 1870.

DEVICE FOR SECURING UNIFORM MOTION IN PUMPING-ENGINES

The Schedule referred to in these Letters Patent and making part of the same.

To all whom it may concern:

Be it known that I, WILLIAM H. ROBERTS, of Mauch Chunk, in the county of Carbon, and State of Pennsylvania, have invented a new and Improved Steam Pumping-Engine; and I do hereby declare that the following is a full, clear, and exact description of the construction and operation of the same, reference being had to the accompanying drawings making a part of this specification, in which—

Figure 1 is a horizontal axial section; and

Figure 2 is a sectional elevation of a modification of the same.

This invention has for its object to secure uniformity of motion in the plunger of a steam-pump throughout the stroke.

The invention is an improvement over that patented by me March 30, 1869, and consists in a regulating-cylinder or water-cushion connected with the valve apparatus of the engine, for the purpose specified.

In the drawings—

a a are two small cylinders, placed end to end upon the main pump-cylinder, *a*, a pipe, *a¹*, provided with a choke-valve, *a²*, connecting their contiguous ends.

Within each cylinder is a plunger, *b*, of a diameter but little less than that of the cylinder, and of a length somewhat greater.

To the outer end of each plunger is secured a cross-bar, *b'*, which cross-bars are united by stay-rods *b''*, one on each side of the cylinders.

One of the cross-bars is directly connected with the valve-mechanism of the engine, and the apparatus constrains the latter to move steadily, forcing the water from one cylinder to the other through the pipe *a¹*, at one stroke, and back again on the return stroke.

The choke-valve *a²* regulates the speed at which the plungers may move.

Fig. 2 shows another form of the invention, in which the cylinders *a a* and plungers *b* are vertical, the tops of the plungers being connected by a walking-beam, and the bottoms of the cylinders by the connecting-pipe.

My patent of March 30, 1869, as well as that of R. Allison, dated September 29, 1868, both describe an invention consisting of a single cylinder, filled with liquid, which is alternately forced by the action of the piston from one end of the cylinder to the other through an external pipe, whose extremities open out of the cylinder near its ends. The points wherein my present invention is an improvement upon these are:

First, it enables me to place the regulating apparatus in an inclined or vertical position, as is frequently necessary, without subjecting it to the disadvantage which attends the other form when similarly placed, that is, the unequal motion of the piston in the down and up strokes, which defeats the very object of the apparatus, and which is remedied by employing two pistons in separate cylinders, the lower one being of less diameter than the upper, so that on the down stroke, the flow of water is hindered by the smallness of the lower cylinder, and on the up stroke the resistance is diminished by the smallness of the lower piston.

Second, if there arises any imperfection in the packing, it, being in the outer ends of the cylinder, and easily accessible, may be readily repaired, whereas the packing of the piston within the cylinder is not so easily got at, nor so readily detected.

Added to the foregoing advantages is the extreme simplicity of the apparatus.

Having thus described my invention,

What I claim as new, and desire to secure by Letters Patent, is—

The combination of the cylinders *a a* with the plungers *b b*, connecting-rod *b'*, and connecting-pipe *a¹*, in the manner and for the purpose described.

To the above specification of my improvement I have set my hand this 1st day of December, A. D. 1869.

W. H. ROBERTS.
